GEORGE FISCHER, BOTH OF ZURICH, SWITZERLAND

MATCHMAKING MACHINE

Application filed June 13, 1929, Serial No. 370,612, and in Germany June 22, 1928.

The present invention relates to improvements in match-making machines and has particular reference to a device for dipping the rows of splints.

5 Devices for dipping the rows of splints are known which are provided with special actuated members, for instance stirring blades, for thoroughly mixing the dipping liquid or paste contained in a vessel in order to maintain it in a uniform condition. These actuated mixing or stirring members get covered with the dipping paste which solidifies even during short intervals in the working of the match-making machine; the solidified 10 ignitable mass may be ignited by but small friction, for instance, even by a match falling on it, whereby the whole content of the vessel may explode. Furthermore these actuated mixing members cause very readily a foaming 15 of the dipping mass which impedes a uniform application of the mass to the splints and causes a tedious cleaning work when the machine is stopped.

The object of the present invention is to 20 overcome these drawbacks. To this end the device for dipping the splints is provided, according to the invention, with a vessel serving as container for the dipping mass and having inner channels one joining to the other 25 for the purpose of guiding the dipping mass in the circumferential direction of the vessel when it is raised and flows back by the up and down movement of the dipping table.

Thus a thorough mixing of the dipping 30 mass is obtained in the required manner without causing any foaming of the mass. Any danger of catching fire or of an explosion is diminished, a uniform application of the dipping mass to the splints is ensured and the work of cleaning the match-making machine is facilitated.

A constructional example of the dipping device according to the present invention will 35 now be described with reference to the accompanying drawings, in which only those parts of the match-making machine are illustrated which are necessary for the comprehension of the invention. In the drawings:

40 Fig. 1 is an elevation of that part of a

match-making machine in which the dipping device is arranged,

Fig. 2 is a vertical section along line II—II in Fig. 1,

Fig. 3 shows in a vertical section the container for the dipping mass, 55

Fig. 4 is a partial section taken at right angles to that of Fig. 3, and

Fig. 5 is a plan view of Fig. 3.

In the drawings 1 denotes the vessel or container for the dipping mass or paste which is of a rectangular shape in plan-view. The vessel 1 is fitted with wheels 2 running on rails 3. Within the vessel 1 the dipping table 4 is adapted to be raised and lowered. 60 To this end the dipping table 4 is suspended from two arms 5 linked at their lower ends to the table and at their upper end to plates 6 each cooperating with a vertical guidance 7 secured to the frame 8 of the match-making 70 machine. The vertical reciprocating motion of the plate 6 is derived from a cam disk 9 with the groove 10 of which a roller 11 at one arm of a bell crank lever 12 cooperates. The other arm of the bell crank lever 12 is linked 75 by means of a connecting rod 13 to the plate 6. The cam disk 9 is rotated from a main driving shaft 14 through the intermediary of a spur gearing 15, shaft 16, bevel gear 17 and shaft 18 to which the cam disk 9 is secured. A scraper 19 is further provided 80 adapted to cooperate with the dipping table 4 and carrying out a reciprocating movement in the horizontal direction across the table. The scraper 19 is mounted in a head 20 guided on a horizontal guide rail 21 and moved to and fro by means of a rocking lever 22, a further guide block 23 and links 24 and 25.

The splints 26 are inserted in a known manner in perforated bars 27 which are 90 moved along guide rails in a known manner, which does not form part of the present invention.

The container 1 is provided with a bottom 28 having surfaces 29 and 30 inclined in the 95 transverse direction of the container towards the longitudinal axis of the latter. In accordance therewith the dipping table 4 is provided with two inclined surfaces 31 and 32. The container 1 is provided on its four 100

circumferential sides with ribs 33, all of which are inclined in a similar direction and the ribs on the same side of the container are parallel to each other with the exception of 5 the ribs provided in the four corners of the container. By means of these ribs 33 inner inclined channels 34 are formed on all four sides of the circumference of the container 1 which join to each other at both ends and 10 reach in a plan view near to the path of movement of the dipping table 4, which is shown in chain-dotted lines in Fig. 3 in its uppermost position.

During the downward movement of the 15 dipping table 4 a displacement of the dipping mass in the container 1 occurs. The dipping mass, which is pressed in the upward direction at the sides of the container by the lowered dipping table 4, is conducted by the 20 channels 34 in an inclined upward direction so that it flows over in the direction of the arrows shown in Fig. 4 from a channel 34 into the adjacent channel 34, i. e. to the next channel of the row of channels 34. Upon the 25 subsequent upward movement of the dipping table 4 the dipping mass flows in the channels 9 in the downward direction, i. e. in a direction opposite to the former flow, and is moved during the following downward 30 movement of the table 4 in an inclined upward direction in the channels 34 and is thus transitorily moved by one step further along the circumference of the container 1 in the direction indicated by the arrow in Fig. 5, 35 and so on. The dipping mass removed so far from the upwardly moved dipping table 4 by the scraper 19 that only a layer of, for instance, 3 millimetres thickness remains on the table, (the dipping layer for the splints), 40 is also conducted by the channels 34 in an inclined downward direction; the same occurs with the dipping mass scraped off the table when cleaning the latter.

In consequence of the above described inclined upward and downward movement of the dipping mass and of its step by step transitory movement along the circumference of the container the dipping mass is subjected to a thorough mixing action without 50 foaming. The uniform condition of the dipping mass is thus always maintained.

I claim:

1. In a device for dipping splints in a match-making machine, in combination, a 55 container for receiving the dipping mass, and a dipping table adapted to move up and down within said container, said container being provided with inclined channels arranged outside of the range of the up and 60 down moving dipping table on the walls of the container for conducting the dipping mass displaced by the movement of the table and causing a transitory movement of said mass along the walls of the container.
- 65 2. In a device for dipping splints in a

match-making machine, in combination, a container for receiving the dipping mass, and a dipping table adapted to move up and down within said container, inclined ribs being provided on the inner sides of the walls of said container and having their inner edges near the path of movement of said dipping tables, said ribs forming between them inclined channels for conducting the dipping mass displaced by the movement of the table and causing a transitory movement of said mass along the walls of the container.

3. In a device for dipping splints in a match-making machine, in combination, an oblong container of rectangular shape in plan view for receiving the dipping mass, and a dipping table adapted to move up and down within said container, inclined ribs being provided on the inner sides of the walls of said container and having their inner edges near the path of movement of said dipping tables, said ribs forming between them inclined channels for conducting the dipping mass displaced by the movement of the table and causing a transitory movement of said mass along the walls of the container.

4. In a device for dipping splints in a match-making machine, in combination, a container for receiving the dipping mass, and a dipping table adapted to move up and down within said container, said container being provided with inclined channels arranged outside the range of the up and down moving dipping table on the walls of the container for conducting the dipping mass displaced by the movement of the table and causing a transitory movement of said mass along the walls of the container, said inclined channels inclining in a horizontal direction in relation to the movement of the dipping mass.

In testimony whereof I have signed my name to this specification.

HEINRICH KUGLER.
